A. L. SMITH

STAIR LANDING CONSTRUCTION

Filed July 9, 1926

Fig. 1

Inventor
Arthur L. Smith
by Roberts, Cushman & Woodberry
Act. 15.

UNITED STATES PATENT OFFICE.

ARTHUR L. SMITH, OF MELROSE, MASSACHUSETTS, ASSIGNOR TO THE A. L. SMITH IRON WORKS, OF CHELSEA, MASSACHUSETTS, A CORPORATION OF MASSACHUSETTS.

STAIR-LANDING CONSTRUCTION.

Application filed July 9, 1926. Serial No. 121,354.

This invention relates to structural supports and more especially to such as are adapted for use in stair landings and the like.

5 In making various building constructions it is now common practice to employ sheet metal (or metal sheets) in many places where wood has formerly been employed. While sheets of this sort are generally possessed of a considerably higher tensile 10 strength than wood, they may be less resistant to bending and shearing for the reason that when using metals the tendency in the building art is to employ single elements 15 which are considerably thinner and of lesser dimensions generally than corresponding parts when made of wood, and hence this reduces the effective bending or shearing strength of a given element, especially in 20 areas where such stresses and strains are localized or concentrated. Accordingly, to offset this effect sheet metal parts are commonly corrugated, folded or provided with ribs and the like which serve to greatly stiffen and strengthen the element either as a 25 whole or in those sections where the stresses and strains to be encountered are especially great.

It is an object of the present invention to 30 provide a structural support more especially adapted to engage and retain such ribbed sheets of metal such as a stair platform, firmly and securely in position, and also to distribute the stresses and strains to which 35 it may be subjected in the course of use.

The invention includes generally the provision of a support having one member (consisting of one or several spaced flange elements) which serves for attachment to the 40 structure with which the support is to be incorporated and a second member, preferably flat and angularly disposed with respect to the flange or flanges of the first member and attached thereto preferably along a common 45 edge, the second member having in the spaces between the flanges of the first member, a suitably fashioned stirrup element for strengthening the support and also for receiving the ribs of the platform or other 50 structural element to be supported thereby.

Such supports are especially adapted to receive and support platform constructions,

stairway treads, etc., which are made from corrugated sheet metal or the like. Accordingly, the invention will be described in this 55 aspect of its application in actual practice,— reference being made to the accompanying drawings, in which:

Fig. 1 is a vertical cross section and view of a platform resting upon the support; 60

Fig. 2 is a perspective view, with parts broken away, of the support alone;

Fig. 3 is a vertical cross-section of a modified form of platform and support; and

Figs. 4 and 5 are side views of a further 65 modification of the support.

Referring to the drawings (Fig. 1) the support 1 is affixed to the adjacent wall or beams 2 and the platform 3 is placed loosely on the support or may be additionally fixed 70 in position thereon.

The support 1 includes vertical member 4 consisting of spaced flanges 5, 5', 5'', which lie in the same plane but are spaced apart. Openings 6 therethrough receive nuts or 75 bolts 7 by which the support may be attached to the general structure of the building in which it is to be installed (as shown in Fig. 1). The support also has an upper or horizontal member 8, which is continuous 80 and whose longitudinal edge is joined to or made integral with the upper edge of the vertical member along the common line of contact 9, and which presents a generally flat, horizontal upper bearing surface 11. 85 The horizontal member 8, in the portions spanning the gaps 12, 12' between the spaced flanges 5, 5', 5'' are bent to form stirrups 13 having substantially vertical sides 14 and a horizontal, flat bottom 15. 90

The platform 3 comprises a substantially flat sheet of metal 16, having transverse ribs 17 on the under side, which may be fashioned thereon, as by folding, bending or the like, and which may open upwardly as 95 in Fig. 1, and a body portion of cement or other appropriate material 18 formed upon the upper surface and filling the channels in the upper side of the ribs 17.

The supports may be made, by making an angle-bar of suitable characteristics and dimensions and then removing the portions of the member 4 corresponding to the gap 12, 12' leaving the separated flanges 5, 5'

5". The portion of the other member 8 which spans the gap thus formed is now folded transversely across (at a point adjacent the end of the flange) and then bent 5 downwardly to the desired angle (or against the adjacent flange) and a suitable distance from the first fold line it is again bent outwardly. The same is done at a point adjacent the flange at the opposite end of the 10 gap, thus forming a U-shaped stirrup 13, as will be clear from the drawings.

The members 4 and 8 are then bored to provide holes for receiving bolts and the supports are fixed in place by any convenient 15 means. The platform 3, of which the transverse ribs are preferably adapted to fit and form a close engagement with the stirrup elements, is then placed so that its margin rests upon the horizontal bearing surface 11 20 intermediate the ribs 17, while the ribs 17 closely fit into and engage the stirrups 13. Due to the close engagement thus effected, it will not be necessary to attach the platform to the support, although in permanent constructions, bolts or screws 19 may be passed 25 through the platform and the horizontal member 8. The bolts may be covered by cement or other material or not, as desired.

The modified form of the support shown 30 in Fig. 3 is provided with stirrups 13 adapted to receive ribs 17 of the platform where the sides of the ribs have been pressed together into contact with each other and hence form a narrow, somewhat V-shaped 35 cross section.

Still further modifications are shown in 40 Figs. 4 and 5, in the first of which the stirrup forms an almost completely closed circle in cross section, and in the latter of which the stirrup projects upwardly, to engage an upwardly disposed rib in the platform.

As thus assembled the platform may be 45 permanent or readily removable but in either event it is securely supported and retained in position. In addition to the utilitarian feature of security thus accomplished, the construction is characterized by occupying but little space both upon the adjacent 50 wall and in the space directly beneath the platform. This effects a substantial economy of space and also avoids ugly projections which from an architectural standpoint present serious difficulties to be overcome. Moreover, the strains impressed upon 55 the platforms are resisted by the ribs and transmitted therethrough to the stirrup members of the support, which on account of their close fitting engagement with the ribs 60 and their own reinforced arrangement are capable of receiving and in turn transmitting them to the vertical or wall member, both downwardly and laterally against the wall.

65 It will be readily apparent that other

applications and adaptations of the invention may be made, but such applications and modifications are to be understood as comprehended by and included within the terms of the present specification and claims. 70

I claim:

1. A structural support, comprising a continuous member having a stirrup element therein and another member in a plane at an angle to the first member and joined thereto 75 along a common edge.

2. A structural support, comprising a continuous member, a portion thereof forming a stirrup element, and another member disposed in a plane forming a right angle with 80 the first member and attached thereto along a common longitudinal edge.

3. A structural support, comprising a continuous member, a portion thereof intermediate the ends forming a stirrup element, and another member consisting of a plurality of flanges disposed in a plane at an angle to the first member and attached thereto 85 along a common longitudinal edge.

4. A structural support, comprising a continuous member, a portion thereof intermediate the ends forming a stirrup element, and another member consisting of a plurality of flanges disposed in a plane at a right angle to 90 the first member and attached thereto 95 along a common longitudinal edge.

5. A structural support, comprising two substantially flat members, integrally joined along a common line of contact and at right angle to each other, one of said members comprising a plurality of flange elements, 100 spaced apart with respect to said line of contact, and the other of said members having stirrups therein intermediate said flange elements. 105

6. A structural support, comprising two substantially flat members, integrally joined along a common line of contact and at right angles to each other, one of said members comprising a plurality of flange elements, 110 spaced apart with respect to said line of contact, and the other of said members having stirrups therein intermediate said flange elements, said stirrups butting against the adjacent ends of said flange elements. 115

7. A structural support comprising an angle bar having two angularly disposed members, transverse portions of one of said members being removed therefrom at spaced intervals and stirrup elements formed in the 120 other of said members in those portions thereof corresponding to the removed portions of the first.

8. A platform construction, comprising a support, said support consisting of a continuous member, a portion thereof forming a stirrup element, and a second member joined to and disposed at right angles to the first member, means for fastening said second member to adjacent wall structure and a 125 130

platform having a rib in the under surface thereof, the margin of said platform and end of said rib resting upon said horizontal member and in said stirrup element respectively.

9. A platform construction, comprising a support, said support consisting of a continuous member, portions thereof forming stirrup elements suitably spaced apart and
- 10 a second member consisting of a plurality of flanges joined to and disposed at right angles to the first member intermediate said stirrup elements, means for fastening said second members to adjacent wall structure
- 15 and a platform having a plurality of transverse ribs spaced apart in the under surface thereof, the longitudinal margin of said platform resting upon the second member of the support and the end portions of the ribs fit-

ting into and engaging the stirrup elements ²⁰ of the support.

10. A platform construction, comprising a support, said support consisting of a plurality of spaced, vertical flanges lying in substantially the same plane and means for fastening said flanges to the adjacent structure, and a continuous horizontal member joined to said flanges along a common edge and having stirrup elements in the spaces intermediate said flanges, and a platform having a sheet metal base provided with transverse ribs, spaced apart at intervals to correspond to said stirrup elements,—said ribs and stirrup elements being of interfitting relationship to each other.

Signed by me at Chelsea, Massachusetts, this 7th day of July, 1926.

ARTHUR L. SMITH.
